Primary Examiner — Rashida C. Walshon(74) *Attorney, Agent, or Firm* — Cramer Patent & Design, PLLC; Aaron R. Cramer(57) **CLAIM**

The ornamental design for a lace, as shown and described.

DESCRIPTION

FIG. 1 is a perspective top front view of a lace, showing my new design;
 FIG. 2 is a perspective top rear right view thereof;

FIG. 3 is a rear elevation view thereof;

FIG. 4 is a front elevation view thereof;

FIG. 5 is a right elevation view thereof;

FIG. 6 is a left elevation view thereof;

FIG. 7 is a top plan view thereof; and,

FIG. 8 is a bottom plan view thereof.

The lace is shown in two parts separated by a jagged break to indicate a lace having indeterminant length.

The broken line drawing is intended to indicate a region where a pocket may be secured and forms no part of the claimed design.
